UNITED STATES PATENT OFFICE.

RAYMOND E. JEFFORDS, OF TEXARKANA, ARKANSAS, AND JOHN R. UECKERT, OF TEXARKANA, TEXAS.

WATCHCASE.

Application filed April 20, 1925. Serial No. 24,360.

This invention relates to new and useful improvements in watch cases.

The invention has to do with that type of watches in which the case is made in halves hinged together and held closed by frictional engagement of the complementary halves. This type of watch is frequently made up as a lady's wrist watch. The two main difficulties experienced with such a watch are the tendency of the case to spring open, thus letting in dust and dirt; and also owing to the minuteness and delicate structure of the works, the stem is often pulled entirely from the works in setting the watch; or becomes loose and is lost.

The object of the invention is to provide a hinged watch case with means for fastening its members together in an effectual manner, whereby the case will be substantially dust proof.

Another object of the invention is to provide means for preventing longitudinal displacement of the stem from the case.

A further object of the invention is to utilize the crown of the stem as a latch to hold the case together.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is a face view of a watch constructed in accordance with the invention, a portion being illustrated in section,

Fig. 2 is an enlarged cross-sectional view on the line 2-2 of Fig. 1,

Fig. 3 is an enlarged cross-section view of the stem on the line 3-3 of Fig. 1, and

Fig. 4 is an enlarged longitudinal sectional view of the stem and case.

In the drawings and numeral 10 designates the front case member and 11 the back case member of a wrist watch, but while we have chosen this type of watch with which to illustrate our invention, it is to be understood that it may be applied to any type having the same style of case. The case members or

halves are hinged together at 12 and usually one has a marginal flange (not shown) telescoping into the other.

In carrying out our invention the semi-circular sections 13 and 14 of a cylindrical collar are formed integral with the members 10 and 11 respectively. These collar sections are somewhat enlarged and elongated in Fig. 1 for the sake of clearness. The stem 15 extends axially through the collar and has a crown 16 secured on its outer end. The crown has an under-cut groove or annular socket 17 surrounding the stem and receiving the outer end of the collar. It will be seen that so long as the collar sections 15 are engaged in the groove 17 of the crown the said sections cannot be separated and consequently the case cannot be opened.

In the bore of each collar section is a semi-circular stop rib 18 surrounding the stem. 70 The stem has the usual set flanges 19 between which the nose of the set lever 20 engages. When the stem 15 is pulled outward, as is shown in dotted lines in Fig. 4, the outer flange 19 will abut the stop ribs 18 and further outward movement of said stem will be prevented. Thus the stem cannot be pulled or lost from the case.

When it is desired to open the case the crown 16 is grasped and pulled outward, as 80 in setting the watch. This pulls the stem 15 outward until the outer flange 19 abuts the ribs 18, whereby the outward movement of the stem is arrested. The crown is displaced sufficiently to remove the groove 17 from the ends of the collar sections, which are then free to move laterally under the crown. With parts in this position the case members 10 and 11 may be swung open. This form of fastening will adequately hold the case members closed, thus excluding dust and also keeping the works in place.

Various changes in the size and shape of the different parts, as well as modifications and alterations may be made within the scope 95 of the appended claims.

What we claim, is:

1. In a watch, hinged case members, a reciprocal stem, retaining means carried by said members to surround the stem, and a 100

member upon the stem axially movable therewith to embrace said means and retain the case members against separation.

2. In a watch, hinged case members, collar sections carried by said members, a stem, and a locking member upon the stem having a seat for receiving the ends of said sections.
3. In a watch, hinged case members, collar

sections carried by the members, a stem, and a crown on the stem having a seat for receiving the ends of the sections. ¹⁰

In testimony whereof we affix our signatures.

RAYMOND E. JEFFORDS.
JOHN R. UECKERT.
